**METHOD FOR PRODUCING
GRAIN-ORIENTED ELECTRICAL STEEL
SHEET**

TECHNICAL FIELD

This invention relates to a method for producing a grain-oriented electrical steel sheet favorably used as an iron core material or the like for a transformer.

BACKGROUND ART

Grain-oriented electrical steel sheets are soft magnetic material used as an iron core material for transformers, electric generators and the like. Having a crystal structure where <001> orientation being a magnetization easy axis of iron is highly aligned in a rolling direction of a steel sheet, such a grain-oriented steel sheet is characterized by being excellent in magnetic properties. The crystal structure is formed, in a finish annealing of the production process of the grain-oriented electrical steel sheet, by preferentially developing secondary recrystallization of crystal grains of {110}<001> orientation, so-called Goss orientation to achieve enormous growth thereof.

Common methods for causing the secondary recrystallization generally include a technique of utilizing precipitates called as an inhibitor. For example, Patent Literature 1 discloses a method of utilizing AN or MnS as the inhibitor, and Patent Literature 2 discloses a method of utilizing MnS or MnSe as the inhibitor, both of which are industrially put into practice.

Although the methods of utilizing an inhibitor are extremely useful for stable development of secondary recrystallized grains, it is necessary to heat a slab to a high temperature of not lower than 1300°C. and turn inhibitor-forming ingredients into solid-solution once to finely disperse inhibitors into steel. Moreover, the inhibitor-forming ingredients cause deterioration of magnetic properties after the secondary recrystallization, and hence it is necessary to conduct a purification treatment of removing precipitates and inclusions of the inhibitor and the like from the base metal at a high temperature of not lower than 1100°C. under a controlled atmosphere.

On the other hand, Patent Literature 3 discloses a method of causing secondary recrystallization using a raw material containing no inhibitor-forming ingredient and developing Goss orientation grains. This method develops dependency of grain boundary orientation difference angle in grain boundary that primary recrystallized grains have, by eliminating impurities such as inhibitor-forming ingredients as much as possible, to thereby cause secondary recrystallization in the Goss orientation grains without using the inhibitor, the effect of which is called as "texture inhibition effect". In this method, fine dispersion of the inhibitor into steel is not necessary, and therefore the high-temperature slab heating, which has been inevitable, is not needed anymore, leading to a significant advantage in terms of fuel costs and the equipment maintenance.

In the method of using a raw material containing no inhibitor-forming ingredient, since no inhibitor is used, it is very important to control the texture. As a method of controlling the texture include, for example, Patent Literature 4 proposes a method of improving the texture of the steel sheet subjected to the primary recrystallization annealing after the cold rolling, by increasing the cooling rate for the hot-band annealing and thus controlling carbide to be precipitated during cooling. In the examples of Patent Lit-

2

erature 4, however, the cooling rate is up to 70°C./s, and no rapid cooling of not less than 100°C./s is performed, the reason of which is assumed due to the fact that the cooling rate of less than 100°C./s is considered to be sufficient to control carbide and there has not been no cooling device capable of attaining the cooling rate of not less than the above rate.

In recent years, development of the cooling technique for thin steel sheets has been promoted. For example, Patent Literature 5 discloses a quench-hardening device that can suppress a decrease in the cooling rate for a metal plate while preventing shape failure in the metal plate to be caused during quench-hardening in a continuous annealing installation for continuously threading the metal plate to conduct the annealing. The quench-hardening device performs the rapid cooling to thereby control the structure and to provide a high-strength steel sheet with a desired strength. However, grain-oriented electrical steel sheets do not need to obtain high strength, so that the rapid cooling has not been applied.

SUMMARY OF INVENTION

Technical Problem

It is, therefore, an object of the invention to propose a method for producing a grain-oriented electrical steel sheet which can stably provide a grain-oriented electrical steel sheet having excellent magnetic properties while maintaining superiority in terms of the productivity and production costs by applying the rapid cooling technique to a production of a grain-oriented electrical steel sheet using a raw material containing no inhibitor-forming ingredient.

Solution to Problem

The inventors have made various studies on an influence of a cooling rate in a hot-band annealing or the like upon magnetic properties of a grain-oriented electrical steel sheet. As a result, it has been found out that, in a production method of the grain-oriented electrical steel sheet using a raw material containing no inhibitor-forming ingredient, by increasing the cooling rate in the hot-band annealing, intermediate annealing and the like before cold rolling as compared to conventional ones, concretely increasing the cooling rate from 800°C. to 300°C. to not less than 200°C./s, slip system of dislocation in the cold rolling is changed to improve primary recrystallization texture, whereby the magnetic properties are largely improved, and thus the invention has been accomplished.

That is, the invention proposes a method for producing a grain-oriented electrical steel sheet comprising a series of steps

heating a steel slab having a component composition comprising C: 0.020 to 0.10 mass %, Si: 2.0 to 4.0 mass %, Mn: 0.005 to 0.50 mass %, Al: less than 0.010 mass %, N, S and Se: less than 0.0050 mass % each, and the

remainder being Fe and inevitable impurities to a temperature of not higher than 1280° C., hot rolling the slab to form a hot-rolled sheet, subjecting the hot-rolled sheet to a hot-band annealing, and then a single cold rolling or two or more cold rollings having an intermediate annealing between each cold rolling to form a cold-rolled sheet having a final sheet thickness, subjecting the cold-rolled sheet to a primary recrystallization annealing combined with a decarburization annealing, applying an annealing separator onto a surface of the steel sheet, and subjecting the steel sheet to a finish annealing and a flattening annealing, in which a rapid cooling is conducted at an average cooling rate of not less than 200° C./s from 800° C. to 300° C. in a cooling process from a maximum achieving temperature in at least one process of the hot-band annealing and the intermediate annealing.

The method for producing a grain-oriented electrical steel sheet according to the invention is characterized in that, subsequently to the rapid cooling, a cooling is conducted from 300° C. to 100° C. at an average cooling rate of 5 to 40° C./s.

The method for producing a grain-oriented electrical steel sheet according to the invention is characterized in that a heating rate between 500° C. and 700° C. in a heating process of the primary recrystallization annealing combined with the decarburization annealing is not less than 500° C./s.

Furthermore, the method for producing a grain-oriented electrical steel sheet according to the invention is characterized in that, in a heating process of the finish annealing, after a temperature holding treatment of holding any temperature between 800° C. and 950° C. is conducted for 5 to 200 hours, or after a heating is conducted between 800° C. and 950° C. at an average heating rate of not more than 5° C./hr to develop secondary recrystallization and further conducted up to a temperature not lower than 1100° C. to complete the secondary recrystallization,

a purification treatment of holding the temperature for not less than 2 hours is conducted.

The steel slab used in the method for producing a grain-oriented electrical steel sheet according to the invention is characterized by containing one or more selected from Cr: 0.01 to 0.50 mass %, Cu: 0.01 to 0.50 mass %, Ni: 0.01 to 0.50 mass %, Bi: 0.005 to 0.50 mass %, B: 0.0002 to 0.0025 mass %, Nb: 0.0010 to 0.0100 mass %, Sn: 0.010 to 0.400 mass %, Sb: 0.010 to 0.150 mass %, Mo: 0.010 to 0.200 mass %, P: 0.010 to 0.150 mass %, V: 0.0005 to 0.0100 mass % and Ti: 0.0005 to 0.0100 mass % in addition to the above component composition.

Advantageous Effects of Invention

According to the invention, a grain-oriented electrical steel sheet having excellent magnetic properties can be stably produced at a low cost using a raw material containing no inhibitor-forming ingredient while maintaining superiority in terms of the productivity and production costs, which has a significant effect on industry.

DESCRIPTION OF EMBODIMENT

Explanation will be made to experiments leading to the invention.

Experiment 1

A steel having a component composition comprising C: 0.045 mass %, Si: 3.0 mass %, Mn: 0.05 mass %, Al: 0.0050 mass %, N: 0.0030 mass %, S: 0.0020 mass % and the remainder being Fe and inevitable impurities is melted and produced in a vacuum melting furnace and cast into a steel ingot. The steel ingot is heated to a temperature of 1250° C. and hot rolled to form a hot-rolled sheet having a sheet thickness of 2.0 mm. Then, the hot-rolled sheet is subjected to a hot-band annealing at a maximum achieving temperature of 1000° C. In this case, a cooling process of the hot-band annealing from 1000° C. to room temperature is divided into three zones of 1000 to 800° C., 800 to 300° C. and 300 to 100° C., and the cooling is performed by changing an average cooling rate in each zone as shown in Table 1. Thereafter, the steel sheet is subjected to a cold rolling to form a cold-rolled sheet having a final sheet thickness of 0.23 mm and then subjected to a primary recrystallization annealing combined with a decarburization annealing in a wet atmosphere of 50 vol % H₂-50 vol % N₂ with a dew point of 50° C. at a soaking temperature of 850° C. for a soaking time of 100 seconds. Then, the steel sheet is coated on its surface with an annealing separator composed mainly of MgO and subjected to a finish annealing by heating (no temperature holding) between 800° C. and 950° C. at a heating rate of 30° C./hr to cause a secondary recrystallization, heating to 1200° C. at a heating rate of 20° C./hr between 950° C. and 1050° C. to complete the secondary recrystallization and then performing a purification treatment of holding at the temperature in a hydrogen atmosphere for 5 hours.

A sample is taken out from the thus-obtained steel sheet after the finish annealing to measure a magnetic flux density B₈ (magnetic flux density in excitation at 800 A/m) by a method described in JIS C2550, and the result is also shown in Table 1. As seen from the result, the magnetic flux density is largely increased by conducting rapid cooling at an average cooling rate from 800° C. to 300° C. of not less than 200° C./s in the cooling process of the hot-band annealing.

Although the mechanism of increasing the magnetic flux density by increasing the average cooling rate from 800° C. to 300° C. to not less than 200° C./s in the cooling process of the hot-band annealing as mentioned above when using raw materials containing no inhibitor-forming ingredient has not been clear yet, the inventors consider it as follows.

The temperature zone from 800° C. to 300° C. in the cooling process of the hot-band annealing has a large influence on the precipitation state of carbide, and thus cooling has been conducted at about 100° C./s in the temperature zone for the purpose of increasing solid-soluted C or increasing fine carbide. However, the above mechanism of improving the magnetic properties is considered not to be due to the increase of the solid-soluted C or fine carbide.

The steel sheet having been subjected to the hot-band annealing is before the process of decarburization annealing (primary recrystallization annealing) and has a high C content, and thus part of the steel sheet causes reversible transformation due to heating in the annealing and is changed from α -phase to γ -phase. The γ -phase after the transformation is different from the surrounding α -phase in crystal structure (γ -phase is FCC and α -phase is BCC) as well as thermal expansion coefficient. When rapid cooling is performed from such a state at not less than 200° C./s, the γ -phase is shrunk to remain due to the supercooling without transforming into α -phase. Therefore, strain different from usual one is caused in a phase interface between γ -phase and α -phase due to the difference in thermal expansion coefficient. As a result, the slip system of dislocation in the subsequent cold rolling process is changed to increase {411} orientation grains of the steel sheet after the primary recrystallization annealing (decarburization annealing) and improve the texture, which is considered to improve the magnetic properties. Moreover, it is considered that strain is caused in the phase interface even at a cooling rate of not more than 100° C./s, but the above effect cannot be obtained sufficiently because the strain is easily eliminated due to the slow cooling rate.

On the other hand, further improvement in magnetic properties is recognized by conducting cooling from 300° C. to 100° C. subsequent to the above rapid cooling at an average cooling rate within 5 to 40° C./s. This is considered due to the fact that martensite transformation of the residual γ -phase is caused by such a slow cooling to introduce higher strain and thereby more improve the primary recrystallization texture. It is well-known that the martensite transfor-

mation of γ -phase is caused by rapid cooling. When the cooling to lower than 100° C. is conducted by the rapid cooling of not less than 200° C./s, the steel sheet is super-cooled at the state of γ -phase, and hence it is thought that the martensite transformation is rather hard to be caused.

Experiment 2

10 A steel having a component composition comprising C: 0.060 mass %, Si: 3.2 mass %, Mn: 0.1 mass %, Al: 0.080 mass %, N: 0.0045 mass %, S: 0.0010 mass %, Se: 0.0030 mass % and the remainder being Fe and inevitable impurities is melted and produced in a vacuum melting furnace and cast into a steel ingot. The steel ingot is heated to a temperature of 1200° C. and hot rolled to form a hot-rolled sheet having a sheet thickness of 2.5 mm. The hot-sheet is subjected to a hot-band annealing with a maximum achieving 15 temperature of 1050° C. Then, the sheet is subjected to the first cold rolling to roll to a middle sheet thickness of 1.5 mm and an intermediate annealing with a maximum achieving temperature of 1050° C. The cooling process from 1050° C. of the intermediate annealing to room temperature is conducted at an average cooling rate of 10° C./s between 1050° C. and 800° C., and then at the average cooling rate of 30° C./s between 300° C. and 100° C., and variously changing the average cooling rate between 800° C. and 300° C. of the above temperature zone as shown in Table 2. Thereafter, the second cold rolling (final cold rolling) is conducted to obtain a cold-rolled sheet having a final sheet thickness of 0.20 mm, and the cold-rolled sheet is subjected 20 to a primary recrystallization annealing combined with a decarburization annealing in a wet atmosphere of 50 vol % H_2 -50 vol % N_2 with a dew point of 60° C. at a soaking temperature of 860° C. for a soaking time of 120 seconds. In this case, the average heating rate between 500° C. and 700° C. in the heating process of the primary recrystallization annealing is changed within three levels of 300° C./s, 500° C./s and 1000° C./s. Then, an annealing separator composed 25 mainly of MgO is applied to the steel sheet surface after the primary recrystallization annealing, and then the sheet is subjected to a finish annealing by heating (no temperature-holding) between 800° C. and 950° C. at a heating rate of 30° C./hr to develop secondary recrystallization, subsequently heating to 1200° C. at a heating rate of 20° C./hr between 950° C. and 1050° C. to complete secondary recrystallization and then performing a purification treatment of holding the sheet at the temperature in a hydrogen atmosphere for 5 hours.

30 A sample is taken out from the thus-obtained steel sheet after the finish annealing, and a magnetic flux density B_8 (magnetic flux density in the excitation at 800 A/m) thereof is measured by a method described in JIS C2550, and the measurement results are also shown in Table 2. As seen from the results, the magnetic flux density is largely increased by 35 conducting the rapid cooling at an average cooling rate of not less than 200° C./s between 800° C. and 300° C. in the cooling process of the intermediate annealing and heating at a heating rate of not less than 500° C./s between 500° C. and 700° C. in the heating process of the primary recrystallization annealing subsequent to cold rolling.

Although the mechanism of largely increasing the magnetic flux density by increasing the average cooling rate from 800° C. to 300° C. in the cooling process of the intermediate annealing to not less than 200° C./s and heating at the heating rate of not less than 500° C./s between 500° C. and 700° C. in the heating process of the primary recrystallization annealing as mentioned above has not been yet clear sufficiently, the inventors consider as follows.

When the average cooling rate from 800° C. to 300° C. in the cooling process of the intermediate annealing is increased to not less than 200° C./s, it is considered, as mentioned in Experiment 1, that strain different from usual one is caused in the phase interface between γ -phase and α -phase. The cold rolling conducted at such a state supposedly causes a deformation band different from usual ones. In this deformation band, nucleation of {411} orientation grains having a high recrystallization temperature is easily caused, and hence to increase the heating rate in the heating process of the primary recrystallization annealing to such a very fast rate as not less than 500° C./s is considered to further increase {411} orientation grains to improve the texture, thereby causing great improvement in the magnetic properties.

The invention is developed based on the above novel knowledge.

Explanation will be made on the reason for limiting the component composition of the raw steel material (slab) used in the production of a grain-oriented electrical steel sheet according to the invention.

C: 0.020 to 0.10 Mass %

When a C content is less than 0.020 mass %, the structure turns a single phase in casting or hot rolling, so that steel is embrittled to cause cracking in the slab or cause an edge cracking in the steel sheet after the hot rolling, which brings about difficulties in production. On the other hand, when the C exceeds 0.10 mass %, it is difficult to reduce the C content to not more than 0.005 mass % where no magnetic aging occurs in the decarburization annealing. Therefore, the C content is in the range of 0.020 to 0.10 mass %. Preferably, it is in the range of 0.025 to 0.050 mass %.

Si: 2.0 to 4.0 Mass %

Si is an element required for increasing a specific resistance of steel to thus improve iron loss. When it is less than

2.0 mass %, the above effect is not sufficient, while when it exceeds 4.0 mass %, the workability of steel is deteriorated to cause it difficult to produce the sheet by rolling. Therefore, the Si content is set in the range of 2.0 to 4.0 mass %. Preferably, it is set in the range of 2.5 to 3.8 mass %.

Mn: 0.005 to 0.50 Mass %

Mn is an element required for improving hot workability of steel. When the Mn content is less than 0.005 mass %, the above effect is not sufficient, while when it exceeds 0.50 mass %, the magnetic flux density of the product sheet lowers. Therefore, the Mn content is set in the range of 0.005 to 0.50 mass %, and more preferably in the range of 0.03 to 0.20 mass %.

Al: Less than 0.010 Mass %, N, S and Se: Less than 0.0050 Mass % Each

In this invention where a grain-oriented electrical steel sheet is produced with a raw steel material containing no inhibitor-forming ingredient, it is necessary to limit contents of Al, N, S and Se being an inhibitor-forming ingredients as much as possible, and therefore Al is limited to less than 0.010 mass % and each of N, S and Se is limited to less than 0.0050 mass %. Preferably, Al is less than 0.007 mass %, N is less than 0.0040 mass % and each of S and Se is less than 0.0030 mass %.

The remainder other than the above component composition of the raw steel material (slab) used in the production of a grain-oriented electrical steel sheet according to the invention is Fe and inevitable impurities. For the purpose of improving the magnetic properties, however, the raw steel material may contain one or more selected from Cr: 0.01 to 0.50 mass %, Cu: 0.01 to 0.50 mass %, Ni: 0.01 to 0.50 mass %, Bi: 0.005 to 0.50 mass %, B: 0.0002 to 0.0025 mass %, Nb: 0.0010 to 0.0100 mass %, Sn: 0.010 to 0.400 mass %, Sb: 0.010 to 0.150 mass %, Mo: 0.010 to 0.200 mass %, P: 0.010 to 0.150 mass %, V: 0.0005 to 0.0100 mass % and Ti: 0.0005 to 0.0100 mass % in addition to the above component composition. Each element has an effect of improving the magnetic properties of the grain-oriented electrical steel sheet. However, when each content is smaller than the lower limit, the effect of improving the magnetic properties cannot be obtained sufficiently. On the other hand, when each content exceeds the upper limit, the development of the secondary recrystallized grains is suppressed and the magnetic properties may rather deteriorated.

There will be described the method for producing a grain-oriented electrical steel sheet according to the invention below.

A grain-oriented electrical steel sheet according to the invention can be produced by a method for producing a grain-oriented electrical steel sheet comprising a series of steps of

heating a raw steel material (slab) having the aforementioned component composition to a given temperature, hot rolling the slab to form a hot-rolled sheet, subjecting the hot-rolled sheet to a hot-band annealing and to a single cold rolling or two or more cold rollings having an intermediate annealing between each cold rolling to form a cold-rolled sheet with a final sheet thickness,

subjecting the cold-rolled sheet to a primary recrystallization annealing combined with a decarburization annealing, applying an annealing separator to the steel sheet surface,

subjecting the steel sheet to finish annealing of causing secondary recrystallization and performing purification treatment, and conducting flattening annealing.

The raw steel material (slab) can be produced by a usual continuous casting method or ingot making-blooming method after a steel that has been adjusted to have the aforementioned component composition is melted by a usual refining process. Also, a thin cast slab having a thickness of not more than 100 mm may be produced by a direct casting method.

Then, the slab is heated to a given temperature and hot rolled to form a hot-rolled sheet having a given sheet thickness. Since a raw steel material containing no inhibitor-forming ingredient is used in the invention, the heating temperature for the slab is not necessary to be a high temperature used for solid-solution of inhibitors, and enough to be not higher than 1280° C. A preferable slab heating temperature is not higher than 1250° C. The lower limit of the heating temperature may be a temperature that can secure the workability in the hot rolling, and is preferably not lower than 1100° C.

Next, the hot-rolled sheet obtained by the hot rolling is subjected to a hot-band annealing for the purpose of complete recrystallization of the structure of the hot-rolled sheet. The maximum achieving temperature in the hot-band annealing is preferable to be not lower than 950° C. from a viewpoint of surely obtaining the above effect. More preferably, it is not lower than 1000° C. On the other hand, when the maximum achieving temperature exceeds 1150° C., crystal grains after the hot-band annealing are coarsened, which makes it difficult to provide a primary recrystallization texture of size-regulated grains. Accordingly, the temperature is limited to not higher than 1150° C. More preferably, it is not higher than 1100° C. Moreover, the duration for holding the maximum achieving temperature is preferable to fall within the range of 5 to 300 seconds from a viewpoint of sufficiently obtaining the effect of the hot-band annealing and ensuring productivity.

The hot-rolled sheet after the hot-band annealing is subjected to pickling for descaling and then to a single cold rolling or two or more cold rollings having an intermediate annealing between each cold rolling to form a cold-rolled sheet having a final sheet thickness. When two or more cold rollings are to be conducted, an annealing temperature in the intermediate annealing is preferable to fall within the range of 1000 to 1150° C. When the annealing temperature is lower than 1000° C., it is difficult to complete recrystallization, while when it exceeds 1150° C., crystal grains after the annealing are coarsened, and hence it is difficult to obtain primary recrystallization texture of size-regulated grains. More preferably, it falls within the range of 1020 to 1100° C. Moreover, a soaking time of the intermediate annealing is preferable to be in the range of 5 to 300 seconds from a viewpoint of sufficiently obtaining the effect of annealing and ensuring productivity.

It is most important in the invention that, in the annealing before the cold rolling, concretely in at least one of the hot-band annealing and the intermediate annealing, it is necessary to conduct a rapid cooling at an average cooling rate of not less than 200° C./s between 800° C. and 300° C. in the cooling process from the maximum achieving temperature. As described above, cooling at the average cooling rate of not less than 200° C./s in the above temperature range causes large strain to be introduced into the interior of the steel sheet after the cooling and leads to an improvement in the texture of the steel sheet after the primary recrystalliza-

tion annealing, whereby the magnetic properties of the product sheet can be improved. The average cooling rate is preferably not less than 300° C./s. In order to industrially attain the cooling rate, the rapid cooling device for jetting water as described in the above Patent Literature 5 and the like can be used favorably. Although the upper limit of the cooling rate is not particularly defined, the upper limit of the cooling rate in the above rapid cooling device is about 1200° C./s.

Next, it is important in the invention that the cooling from 300° C. to 100° C. subsequent to the rapid cooling between 800° C. and 300° C. is preferably conducted at an average cooling rate of 5 to 40° C./s. Thus, strain quantity in the steel sheet after the annealing can be more increased to further improve the magnetic properties. More preferably, the average cooling rate falls within the range of 20 to 40° C./s.

Thereafter, the steel sheet with the final sheet thickness after the cold rolling (cold-rolled sheet) is subjected to a primary recrystallization annealing combined with a decarburization annealing. The primary recrystallization annealing is preferable to be conducted at a soaking temperature of 800 to 900° C. for a soaking time 50 to 300 seconds, from a viewpoint of securing decarburization property. The annealing atmosphere is preferable to be a wet atmosphere from a viewpoint of securing the decarburization property. The decarburization annealing allows the C content in the steel sheet to be reduced to not more than 0.0050 mass %. Further, the texture is further improved by increasing the temperature at a heating rate of not less than 500° C./s between 500° C. and 700° C. being the recrystallization temperature zone in the heating process of the primary recrystallization annealing to thus improve the magnetic properties. Desirably, the heating rate is not less than 600° C./s.

Then, the steel sheet after the primary recrystallization annealing is, in a case where a forsterite coating is to be formed in a finish annealing, coated with an annealing separator composed mainly of MgO on the steel sheet surface and thereafter subjected to the finish annealing of causing a secondary recrystallization and conducting a purification treatment. Whereas, in a case where blanking workability is considered important and thus the forsterite coating is not to be formed, the annealing separator is not applied or an annealing separator composed mainly of silica, alumina or the like is applied to the steel sheet surface and then the finish annealing is conducted.

It is preferable to conduct a temperature holding treatment of holding an arbitrary temperature between 800° C. and 950° C. for 5 to 200 hours in the heating process of the finish annealing. Alternatively, it is preferable to heat between 800° C. and 950° C. at an average heating rate of not more than 5° C./hr to develop secondary recrystallization, subsequently, or after lowering the temperature to not higher than 700° C. once, reheat, increase the temperature between 950° C. and 1050° C. at an average heating rate of 5 to 35° C./hr up to not lower than 1100° C. to complete the secondary recrystallization, and thereafter conduct a purification treatment of holding the temperature for not less than 2 hours. The purification treatment allows Al, N, S and Se in the steel sheet to be decreased to the level of inevitable impurities.

A preferable temperature holding time between 800° C. and 950° C. is 50 to 150 hours, and a preferable average heating rate between 800° C. and 950° C. is 1 to 3° C./hr. Also, a preferable temperature and a preferable holding time in the purification treatment are 1200 to 1250° C. and 2 to

11

10 hours, respectively. Moreover, an atmosphere of the purification treatment in the finish annealing is preferable to be H₂ atmosphere.

The steel sheet after the finish annealing is subjected to a water washing, a brushing, a pickling or the like to remove unreacted annealing separator, and then subjected to a flattening annealing for a shape correction, which is effective for reducing the iron loss. When the steel sheets are laminated for use, it is preferable to apply an insulation coating onto the steel sheet surface in the flattening annealing or before or after the flattening annealing, in order to improve the iron loss. Moreover, it is preferable to use a tension-imparting coating as the insulation coating to further reduce the iron loss. In this case, it is possible to adopt a method of forming the tension-imparting coating through a binder, or a method of depositing an inorganic matter onto the steel sheet surface by a physical vapor deposition method or a chemical vapor deposition method to use as the tension-imparting coating. In order to further reduce the iron loss, it is preferable to conduct a magnetic domain subdividing treatment by irradiating a laser beam, plasma beam or the like onto the surface of the product sheet to apply heat strain or impact strain, or by forming grooves in the steel sheet surface.

Example 1

A steel slab having a component composition shown in Table 3 and the remainder being Fe and inevitable impurities

12

of 60 vol % H₂-40 vol % N₂ with a dew point of 55° C. for 150 seconds. In this case, the average heating rate between 500° C. and 700° C. in the heating process is 200° C./s.

Next, an annealing separator composed mainly of MgO is applied onto the steel sheet surface after the primary recrystallization annealing, and thereafter the steel sheet is subjected to a finish annealing by heating (no temperature holding) between 800° C. and 950° C. at a heating rate of 30° C./hr to cause secondary recrystallization, subsequently heating to 1200° C. at a heating rate of 20° C./hr between 950° C. and 1050° C. to complete the secondary recrystallization and conducting a purification treatment of holding at such a temperature in a hydrogen atmosphere for 10 hours.

A test specimen is taken out from the thus-obtained steel sheet after the finish annealing, and a magnetic flux density B₈ (magnetic flux density excited at 800 A/m) thereof is measured by a method described in JIS C2550 to obtain results shown in Table 4. As seen from Table 4, all of the steel sheets obtained by using the raw steel material having the component composition adapted to the invention and performing the rapid cooling in the hot-band annealing under the conditions adapted to the invention have an excellent magnetic flux density, and particularly the faster the cooling rate between 800° C. and 300° C., the more excellent the magnetic flux density.

850° C. in a wet atmosphere of 55 vol % H₂-45 vol % N₂ with a dew point of 60° C. for 60 seconds. In this case, the average heating rate between 500° C. and 700° C. in the heating process is 400° C./s.

5 An annealing separator composed mainly of MgO is applied to the steel sheet surface after the primary recrystallization annealing. Then, the steel sheet is subjected to a finish annealing comprising heating (no temperature holding) between 800° C. and 950° C. at a heating rate of 25° C./hr to develop secondary recrystallization, subsequently heating to 1225° C. at a heating rate of 20° C./hr between 10 950° C. and 1050° C. to complete the secondary recrystallization and performing a purification treatment of holding 15 such a temperature in a hydrogen atmosphere for 10 hours.

A test specimen is taken out from the thus-obtained steel sheet after the finish annealing, and a magnetic flux density 20 B₈ (magnetic flux density excited at 800 A/m) thereof is measured by a method described in JIS C2550 to obtain results shown in Table 5. As seen from Table 5, all of the steel sheets obtained by using the raw steel material having 25 the component composition adapted to the invention and performing the hot-band annealing and/or intermediate annealing under the conditions adapted to the invention are excellent in the magnetic flux density.

5 A steel slab comprising C: 0.049 mass %, Si: 3.5 mass %, Mn: 0.069 mass %, sol. Al: 0.0070 mass %, N: 0.0035 mass %, S: 0.0010 mass % and the remainder being Fe and inevitable impurities as used in Example 2 is produced by a continuous casting method, reheated to a temperature of 1280° C. and hot rolled to form a hot-rolled sheet having a sheet thickness of 2.5 mm. The hot-rolled sheet is subjected to a hot-band annealing at 1000° C. for 60 seconds. In this case, average cooling rates between 800° C. and 300° C. and between 300° C. and 100° C. in the cooling process of the hot-band annealing are varied as shown in Table 6. Thereafter, the steel sheet is subjected to the first cold rolling to 55 roll to a middle sheet thickness of 1.8 mm, an intermediate annealing at 1080° C. for 60 seconds and the second cold rolling to form a cold-rolled sheet having a final sheet thickness of 0.23 mm. In this case, the average cooling rate between 800° C. and 100° C. in the cooling process of the intermediate annealing is 40° C./s.

60 Then, the cold-rolled sheet is subjected to a primary recrystallization annealing combined with a decarburization

annealing at 850° C. in a wet atmosphere of 55 vol % H₂-45 vol % N₂ with a dew point of 58° C. for 100 seconds. In this case, the average heating rates between 500° C. and 700° C. in the heating process are varied as shown in Table 6. An annealing separator composed mainly of MgO is applied onto the surface of the steel sheet after the primary recrystallization annealing, and the steel sheet is subjected to a finish annealing of completing the secondary recrystallization and then performing a purification treatment of holding at a temperature of 1225° C. in a hydrogen atmosphere for 10 hours. In this case, heating conditions for completing the secondary recrystallization in the finish annealing (heating conditions for developing secondary recrystallization between 800° C. and 950° C., presence or absence of subsequent temperature dropping to 680° C., and average heating rate between 950° C. and 1050° C.) are varied as shown in Table 6.

A test sample is taken out from the thus-obtained steel sheet after the finish annealing, and a magnetic flux density B₈ (magnetic flux density excited at 800 A/m) thereof is measured by a method described in JIS C2550 to obtain results shown in Table 6. As seen from Table 6, the magnetic flux density of the product sheet is more increased by performing the temperature holding treatment for not less than 5 hours between 800° C. and 950° C. or by raising the temperature at not more than 5° C./s between 800° C. and 950° C. in the heating process of the finish annealing, regardless of the presence or absence of subsequent temperature dropping to 680° C. Also, the magnetic flux density is further increased by increasing the average heating rate between 500° C. and 700° C. in the heating process of the primary recrystallization annealing to not less than 500° C./s.

subjecting the hot-rolled sheet to a hot-band annealing, and then a single cold rolling or two or more cold rollings having an intermediate annealing between each cold rolling to form a cold-rolled sheet having a final sheet thickness,

subjecting the cold-rolled sheet to a primary recrystallization annealing combined with a decarburization annealing,

applying an annealing separator onto a surface of the steel sheet, and

subjecting the steel sheet to a finish annealing and a flattening annealing, wherein

a rapid cooling is conducted at an average cooling rate of not less than 200° C./s throughout the entire temperature range of from 800° C. to 300° C. in a cooling process from a maximum achieving temperature of above 800° C. in at least one process of the hot-band annealing and the intermediate annealing, and subsequently to the rapid cooling, a cooling is conducted from 300° C. to 100° C. at an average cooling rate of 5 to 40° C./s.

2. The method for producing a grain-oriented electrical steel sheet according to claim 1, wherein

a heating rate between 500° C. and 700° C. in a heating process of the primary recrystallization annealing combined with the decarburization annealing is not less than 500° C./s.

3. The method for producing a grain-oriented electrical steel sheet according to claim 1, wherein in a heating process of the finish annealing, either

(i) after a temperature holding treatment holding any temperature between 800° C. and 950° C. is conducted for 5 to 200 hours, or

TABLE 6

No	Cooling rate in hot-band annealing (° C./s)		heating rate between 500° C. and 700° C. in primary	Finish Annealing conditions

13	300	30	1500	Heating at 5° C./hr, no temperature holding	Absence	35	1.938

The invention claimed is:

1. A method for producing a grain-oriented electrical steel sheet comprising a series of steps

heating a steel slab having a component composition comprising C: 0.020 to 0.10 mass %, Si: 2.0 to 4.0 mass %, Mn: 0.005 to 0.50 mass %, Al: less than 0.010 mass %, N, S and Se: less than 0.0050 mass % each, and the remainder being Fe and inevitable impurities to a temperature of not higher than 1280° C.,

hot rolling the steel slab to form a hot-rolled sheet,

(ii) after a heating is conducted between 800° C. and 950° C. at an average heating rate of not more than 5° C./hr to develop secondary recrystallization and further conducted up to a purification temperature not lower than 1100° C. to complete the secondary recrystallization, a purification treatment of holding the purification temperature for not less than 2 hours is conducted.

4. The method for producing a grain-oriented electrical steel sheet according to claim 2, wherein in a heating process of the finish annealing, either

17

- (i) after a temperature holding treatment holding any temperature between 800° C. and 950° C. is conducted for 5 to 200 hours, or
- (ii) after a heating is conducted between 800° C. and 950° C. at an average heating rate of not more than 5° C./hr to develop secondary recrystallization and further conducted up to a purification temperature not lower than 1100° C. to complete the secondary recrystallization, a purification treatment of holding the purification temperature for not less than 2 hours is conducted.

5. The method for producing a grain-oriented electrical steel sheet according to claim 1, wherein the component composition of the steel slab further contains one or more selected from

Cr: 0.01 to 0.50 mass %,
Cu: 0.01 to 0.50 mass %,
Ni: 0.01 to 0.50 mass %,
Bi: 0.005 to 0.50 mass %,
B: 0.0002 to 0.0025 mass %,
Nb: 0.0010 to 0.0100 mass %,
Sn: 0.010 to 0.400 mass %,
Sb: 0.010 to 0.150 mass %,
Mo: 0.010 to 0.200 mass %,
P: 0.010 to 0.150 mass %,
V: 0.0005 to 0.0100 mass % and
Ti: 0.0005 to 0.0100 mass %.

6. The method for producing a grain-oriented electrical steel sheet according to claim 2, wherein the component composition of the steel slab further contains one or more selected from

Cr: 0.01 to 0.50 mass %,
Cu: 0.01 to 0.50 mass %,
Ni: 0.01 to 0.50 mass %,
Bi: 0.005 to 0.50 mass %,
B: 0.0002 to 0.0025 mass %,
Nb: 0.0010 to 0.0100 mass %,
Sn: 0.010 to 0.400 mass %,
Sb: 0.010 to 0.150 mass %,

35

18

Mo: 0.010 to 0.200 mass %,
P: 0.010 to 0.150 mass %,
V: 0.0005 to 0.0100 mass % and
Ti: 0.0005 to 0.0100 mass %.

5. 7. The method for producing a grain-oriented electrical steel sheet according to claim 3, wherein the component composition of the steel slab further contains one or more selected from

Cr: 0.01 to 0.50 mass %,
Cu: 0.01 to 0.50 mass %,
Ni: 0.01 to 0.50 mass %,
Bi: 0.005 to 0.50 mass %,
B: 0.0002 to 0.0025 mass %,
Nb: 0.0010 to 0.0100 mass %,
Sn: 0.010 to 0.400 mass %,
Sb: 0.010 to 0.150 mass %,
Mo: 0.010 to 0.200 mass %,
P: 0.010 to 0.150 mass %,
V: 0.0005 to 0.0100 mass % and
Ti: 0.0005 to 0.0100 mass %.

20 8. The method for producing a grain-oriented electrical steel sheet according to claim 4, wherein the component composition of the steel slab further contains one or more selected from

Cr: 0.01 to 0.50 mass %,
Cu: 0.01 to 0.50 mass %,
Ni: 0.01 to 0.50 mass %,
Bi: 0.005 to 0.50 mass %,
B: 0.0002 to 0.0025 mass %,
Nb: 0.0010 to 0.0100 mass %,
Sn: 0.010 to 0.400 mass %,
Sb: 0.010 to 0.150 mass %,
Mo: 0.010 to 0.200 mass %,
P: 0.010 to 0.150 mass %,
V: 0.0005 to 0.0100 mass % and
Ti: 0.0005 to 0.0100 mass %.
